CLAIM

We claim the ornamental design for a grating plate, as shown and described.

DESCRIPTION

FIG. 1 is a top perspective view of a grating plate.

FIG. 2 is another top perspective view thereof.

FIG. 3 is a bottom perspective view thereof.

FIG. 4 is a first side elevation view thereof.

FIG. 5 is a second side elevation view thereof.

FIG. 6 is a third side elevation view thereof.

FIG. 7 is a fourth side elevation view thereof.

FIG. 8 is a top plan view thereof; and,

FIG. 9 is a bottom plan view thereof.

Any broken lines in the drawings illustrate portions of the grating plate that form no part of the claimed design.
